UNITED STATES PATENT OFFICE.

PATRICK P. LA MONTAGNE, OF BOURBONNAIS, ILLINOIS, ASSIGNOR TO PARAMOUNT KNITTING COMPANY, OF CHICAGO, ILLINOIS, A CORPORATION OF ILLINOIS.

KNITTING-MACHINE AND NEEDLE THEREFOR.

1,321,646.

Specification of Letters Patent. Patented Nov. 11, 1919.

Application filed December 7, 1917. Serial No. 205,982.

To all whom it may concern:

Be it known that I, PATRICK P. LA MONTAGNE, a citizen of the United States, residing at Bourbonnais, county of Kankakee, 5 State of Illinois, have invented an Improvement in Knitting - Machines and Needles Therefor, of which the following description, in connection with the accompanying drawing, is a specification, like characters 10 on the drawing representing like parts.

This invention relates to a knitting machine in which so-called separate latch needles are employed, that is, needles in which the latch member is physically separate 15 from the hook member and a relative movement takes place between the two needle members in effecting their coöperation, and also to a construction of such needles.

20 In one type of the separate latch needle knitting machine the needle consists of a hook member and a separate latch member each provided with a pair of oppositely disposed shoulders, the separation of the members 25 of the one pair of shoulders being greater than the separation of the members of the other pair, and to an extent sufficient to secure the required relative movements of the needle members, as between the yarn-receiving and casting off positions of the 30 needle, and as required in the covering and uncovering of the hook by the latch.

It is frequently necessary in the operation 35 of the machine and in knitting to throw one or more of the needles out of action and then restore such needles into action as, for example, when reciprocating work is performed upon a circular knitting machine. Thus in the case of knitting the heel and toe 40 portions of a stocking it is necessary first to throw out of action the set of needles employed in knitting the instep, then at the end of each reciprocation to throw out of action one or more of the remaining needles in the 45 narrowing operation, then to restore into action at the end of each reciprocation one or more of the needles last thrown out for the widening operation, and then to restore into action the set of needles first thrown 50 out.

It is the principal object of this invention to provide for the required throwing out of action and restoring into action of separate

latch needles wherein each member is provided with a pair of oppositely disposed shoulders for the purpose and having the function above described. Such a needle is usually operated by cams acting upon a butt projecting from the hook member. A knitting machine needle is customarily thrown out of action by projecting the needle above or beyond its normal yarn-receiving position so that it will be out of the path of the actuating cam and will consequently not be depressed or retracted to take yarn in the further operation of the machine. If both members of a separate latch needle be thus projected the needle can not be restored to yarn-receiving position simply by depressing or retracting the hook member to the 70 position from which it was projected out of action because by reason of the relative movement which takes place between the hook and latch members the latch member will, when the hook is restored to normal 75 yarn-receiving position, not itself be in its yarn-receiving position but will be left covering the hook. Consequently if yarn be fed it will at once be cast off and will not be caught by the hook. 80

This invention provides a construction of machine and of needle which provide for throwing the needle out of action and restoring it into action so arranged that, when the hook member is given an abnormal movement or is projected beyond its normal yarn-receiving position to throw the needle out of action, the latch member will be released from movement with the hook member and will not move materially beyond its normal 90 yarn-receiving position and will instead be retained substantially in its normal yarn-receiving position and so arranged that when the hook member is retracted to restore the needle into action the latch member will not 95 be moved materially.

In the preferred form of the invention this result is effected by providing a recess in, or deepening, the groove in the needle bed for the latch member, by beveling the 100 lower set of coöperating shoulders on the hook and latch member, and so positioning the recess or deepened portion of the groove that when the needle members moving together in the projecting movement of the 105 needle with the lower shoulders in contact

reach or pass the normal yarn-receiving position, the latch member will be cammed back by the beveled shoulders into the recess or deepened groove and the latch member will escape from or be freed from the hook member allowing the hook member to continue its projecting movement without further movement of the latch member. In other words the needle members of this invention are provided with means acting to effect the coöperating movements of the latch member during the retracting movements and the projecting movements of the hook member and to release the latch member from movement with the hook member upon an abnormal projecting movement of the hook member.

The principles of this invention may be secured in various ways and by various types of mechanism, but the invention is herein exemplified in a familiar circular type of knitting machine in which two sets of needles are employed, the one set having butts longer than the other set, in which a switch cam is employed which when thrown into one position acts to effect the elevation of the set of needles having the longer butts and which when thrown into another position acts to depress the set of needles having the longer butts and also preferably any needles having the shorter butts which have been left projected, in which picker and dropper mechanism is provided, the former acting selectively to project as required needles having the shorter butts and the latter acting selectively to restore such needles. In this type of mechanism no particular change in the adjustment and operation of the switch cam, picker mechanism, and dropper mechanism is required, and these parts all operate in their customary manner.

The foregoing and other objects of the invention will appear more fully from the accompanying description and drawings and will be particularly pointed out in the claims.

The drawings show so much of an ordinary type of circular knitting machine and 50 needle as is necessary to a disclosure of the invention.

In the drawings,

Figure 1 is a plan view partially in horizontal cross section showing the general 55 construction of this circular type of knitting machine with the various cams, picker mechanism and dropper mechanism;

Fig. 2 is a view chiefly in central vertical cross section of a portion of the knitting 60 machine, showing a preferred form of construction embodying this invention and with the needle approaching or in normal yarn-receiving position;

Fig. 3 is a view of a portion of the construction shown in Fig. 2 with the needle

shown in the position it occupies when thrown out of action;

Fig. 4 is a diagrammatic view showing the different positions of the needle members, cams, picker and dropper occurring in a 70 preferred embodiment of this invention.

The details of construction and operation of the knitting machine not being involved in the present invention and the general construction and operation of such machines 75 being well known and familiar to those skilled in the art it is unnecessary either to illustrate or describe the entire machine.

It will be sufficient to note that the machine here disclosed as a preferred embodiment of the invention comprises a bed plate 1, a cylinder 2, a concentric gear ring 3 rotatably mounted in the bed plate and driven by a gear 4 from the main shaft 5, a cam carrier 6 concentrically mounted on the bed 80 plate and moving with the gear ring, a cam ring 7 concentrically mounted within the cam carrier and driven thereby but vertically movable with respect thereto. The cylinder 85 is held against rotary movement with respect to the needle bed but is vertically adjustable to vary the length of stitch when the needles are performing the ordinary knitting operation. To enable this to be done without changing the relative projected position of the needle with respect to the top of the cylinder and thus possibly increasing the cross sectional area of the combined latch and hook members projecting through 90 the loop the lower or projecting cam is arranged to be moved, or to be vertically adjustable, with the cylinder. For this purpose the cylinder is supported by a suitable support or rod 8. The cam ring 7 is provided with an annular flange at its bottom 100 resting upon a ring support 9. This ring support is connected to move with the cylinder as by the vertical studs 10 and the cam ring is secured to the cam carrier so as to rotate therewith but telescope with respect 105 thereto by means of the studs 11 secured to the flange of the cam ring and projecting through apertures in the cam carrier.

The cam ring has formed therein or connected therewith the usual projecting or elevating cam 12 while the coöperating retracting or depressing cam 13 is mounted upon the cam carrier 6.

The needle comprises a hook member 14 and a separate latch member 15. The hook member 14 slides in the groove 16 in the needle cylinder and the latch member slides in a narrower groove 17 formed in the cylinder back of the groove for the hook member. The hook member presents the usual hook 18 and beneath or in the rear of the hook is longitudinally and transversely slotted. At the opposite end of its shank the hook member is provided with the usual laterally extending butt 19 and at some suit- 130

able point and preferably on the shank near the end is provided with a pair of oppositely disposed shoulders 20 and 21. The lowermost shoulder or that shoulder which acts in the projecting movement of the needle is beveled or inclined as shown.

The latch member is provided with a pointed head 22 sliding through the slot in the hook member into and out of co-operation with the hook and the shank of the latch member is extended and provided with a pair of oppositely disposed shoulders 23 and 24 located between and co-operating respectively with the shoulders 20 and 21 of the hook member to give the required movements to the latch member from the hook member. The lowermost shoulder 24 is beveled or inclined as illustrated to correspond with the shoulder 21 on the hook member.

20 A recess or deepened portion 25 of the latch groove 17 is located at the upper end of the latch groove and is of such a length that when the latch member is projected to reach its normal yarn-receiving position or has 25 passed slightly beyond its normal yarn-receiving position the latch member may fit in this recess 25 and allow the shoulder 21 of the hook member to ride past the face of the latch member. The shoulders 21 and 30 24 are beveled or inclined so that as the needle is moving in its projecting movement with these shoulders in contact they will act to cam the latch member back into the recess 25 when the lower end of the latch member reaches the lower end of the recess. The shoulder 23 on the latch member projects sufficiently to be in the path of the shoulder 20 of the hook member when the hook member in its retracting movement approaches 40 or reaches the normal yarn-receiving position.

The general operation of the needle will be apparent. When the butt of the hook member is projected the hook member is moved along until its shoulder 21 contacting with the shoulder 24 of the latch member picks up the latch member, when the two members move together with the hook uncovered and in the relation shown, for example, in Fig. 2. They continue in this relative position until the needle reaches the normal yarn-receiving position. Upon the reverse or retracting movement the hook member moves alone until its shoulder 20 contacts with the shoulder 23 of the latch member when it picks up the latch member and the members move together with the hook covered by the point of the latch. In the projecting movement of the needle when 60 the latch comes opposite the recess 25 if the projecting movement is continued, as for example, to throw the needle out of action, the shoulders 21 and 24 act to cam the latch back into the recess 25 whereupon it is 65 released from movement with the hook.

member and the hook member continues in its projecting movement alone and may be left thus abnormally projected throwing the entire needle out of action. When the needle is to be thrown into action the hook 70 member is retracted and moves alone until it reaches normal yarn-receiving position and when in its normal yarn-receiving position the latch member is also in its normal yarn-receiving position because it has 75 never moved from that position. The lower end of the recess 25 is inclined or beveled as shown at 26 and the lower end of the shank of the latch is correspondingly inclined or beveled at 27 so that as the hook 80 member is further retracted and the shoulders 20 and 23 come into contact the latch member is cammed out of the recess and rides in the body of its groove 17.

In the normal knitting operation the butts 85 of the hook members of the needles rest upon the top of the cam ring 7 and as the cam is rotated with respect to the cylinder the needles are reciprocated by the action of the knitting cams 12 and 13 in the usual manner.

One set of needles preferably has its butts 28 longer than the butts 19 of the other set in order that the set of needles having the longer butts may be thrown out of action 95 independently of the other set, as, for example, when reciprocating knitting is to be performed.

The general type of means selected as a preferred embodiment of the invention for 100 throwing the various needles out of action and restoring them into action as required is of a familiar type and need only be described in a general way. Such a mechanism in its main features is shown in the patent to 105 Mayo No. 726,178 granted April 21, 1903.

For throwing the set of needles having the longer butts out of action and restoring them into action a suitable wedge-shaped cam 29 is employed mounted upon a shaft 110 30 rotatably and longitudinally movable in a bearing 31 radially supported from the gear ring 3. This cam 29 during the ordinary circular knitting operation stands in elevated position and travels in a path above 115 the butts. When the set of needles having the longer butts are to be thrown out of action the shaft 30 is rotated and at the same time moved longitudinally outwardly to bring the point of the cam 29 into its depressed position below the path of the butts 120 28. This movement of the cam may be effected manually or automatically, in the latter case by some such means as the automatic positioning of the cam 32 in the path of the 125 crank arm 33 extending from the shaft 30. In this depressed position as the gear ring is rotated the upper surface of the cam 29 rides beneath the butts 28 and raises or projects the butts to a position where they are 130

caught by the upper surface 34 of the cam 13 and are further elevated thereby and ride therealong.

When this section of needles is to be restored to knitting position the cam 29 is swung upwardly and at the same time moved inwardly, the latter action being effected as by a stud 35 on the shaft 30 riding in an inclined groove 36 in the bearing 31 to bring the lower surface of the cam 29 above the butts of all the needles, both those having the longer butts 28 and those having the shorter butts 19, so that as the cam ring is rotated the needles are all retracted or restored to a position where they are within the path of the depressing or retracting cam 13. This operation may be performed either manually or by the usual type of automatic mechanism of the machine.

For selectively throwing the shorter butt needles out of action and restoring them into action, as in reciprocating knitting, suitable mechanism such as a well known type of picker mechanism and dropper mechanism may be employed and is herein illustrated. In the type illustrated the picker mechanism and the dropper mechanism are shown as separate instrumentalities. When the reciprocating knitting is taking place the gear ring 3 is given an oscillating or reciprocating motion. Upon this gear ring at one side are mounted the pickers 37 and at an opposite point the dropper 38 and all are constructed and operate in a manner well known to those skilled in the art.

The pickers 37 at their effective ends are notched at 39 sufficiently to receive the butts of one or more needles according to the number to be thrown out of action at each end of each reciprocation. Each picker 37 is mounted to pivot vertically in a post 40 and each post is mounted to pivot horizontally on the gear ring 3. The shanks of the picker extend through cam slots 41 in a guide plate 42 also secured to the gear ring 3. The length of the pickers is such that when in radial position the pickers will just clear the bodies of the needles and the heads of the pickers will pass above or beneath the butts so that during circular knitting the needles are idle. The posts 40 are placed apart a distance longer than the amount of lost motion between the gear ring and cam carrier so that at each change of direction of movement the cam carrier operates to carry first one and then the other of the pickers into position in front of the cam section 13 trailing the other picker upon the outside of the said cam, but neither picker can be trailed behind the cam section without causing it to swing horizontally with the post 40 and clear the said cam. This swinging movement in co-operation with the cam surface 41 on the guide plate 42 causes the swinging

picker to be depressed into its lowermost position. When the direction of reciprocation is again changed this depressed picker is by the lost motion between the gear ring and cam carrier brought in front of the retracting cam surface of the cam 13 in its lowermost position and its notch 39 will thereupon engage the butt or butts to be elevated or projected. As the rotation of the gear ring continues the butts thus seized hold the picker against rotation and the picker slides up the cam surface 41 on the guide plate 42 and takes with it the engaged butt until the butts are in line with the upper surface 34 of the cam 13. The needle butts are then lifted by this cam surface onto and ride therealong and the needles are held in the elevated or projected position in the usual manner. The picker then clears itself from the butts as the needles are forced upwardly by the inclined ends of the cam surface 34 and springs back into its normal radial position. This operation continues reversely with the two pickers and thus at each end of each reciprocation one or more needles are elevated or projected and thus thrown out of action causing the narrowing operation.

The widening operation then takes place in a similar but reverse manner through the action of the dropper 38 which is a symmetrically shaped device horizontally and vertically pivoted in a bearing 43 on the gear ring 3. This dropper 38 is notched at each side and at the bottom of its end to receive the butts of one or more of the needles according to the number to be depressed at the end of each reciprocation. It stands out of the path of the needles and, when called into operation preferably by automatic mechanism such for example as the sliding cam plate 44 automatically actuated by the crank arm 45 by the mechanism of the machine at the required time, it is guided to a position in line with the butts of the elevated or projected needles so that at the end of each reciprocation the butts of the needles at the end of the row of needles out of action ride into one of the notches in the end of the dropper. As the reciprocating movement continues the dropper is forced downwardly in the cam slot of its guide plate, herein not shown for clearness of illustration, and forced downwardly carrying with it and thus depressing the butts of the engaged needles and as it is carried downwardly it swings radially and clears itself after depressing the needles. The dropper then springs back into elevated position and is operated on the reverse reciprocation in a similar manner. In the widening operation the dropper is generally arranged to depress a greater number of needles than the pickers elevate, for example, the picker may remain in operation each elevating say one needle

at the end of each reciprocation and the dropper depressing two needles at each end of each reciprocation so that as a net result one needle is brought back into operation at each end of each reciprocation and thus the widening of the knitting secured. But the particular construction and operation of the picker mechanism and the dropper mechanism is not involved in this invention and 10 this general explanation will be sufficient to those skilled in the art.

In the present invention the needles when in their normal projected or yarn-receiving position generally stand as indicated in Fig. 15 2, that is, with the shoulder 21 of the hook member in contact with the shoulder 24 of the latch member and with the lower end of the latch member slightly below the lower end of the recess 25. Thus the latch member 20 is not forced into the recess 25 nor placed in position so that it may slip into the recess 25 during the normal knitting operations but if it is desired the normal projected or 25 yarn-receiving position of the needle may be the position it occupies when the latch member has just been carried back into the recess 25.

In any event the normal yarn-receiving position is that position of the needle to 30 which the hook member has been brought by the action of the projecting cam 12 upon its butt and to which the latch member has been brought by the action of the shoulder 21 of the hook member upon the shoulder 24 of 35 the latch member. In this position the point of the latch member is separated from the hook and lies within the slot in the hook member.

In the present invention the needles 40 thrown out of action whether by the switch cam or by the picker mechanism are usually seized when in their normal yarn-receiving or projected position. When this takes place the hook member is projected well above its 45 normal yarn-receiving position and to a position such as shown, for example, in Fig. 3.

If the recess 25 is so located that the latch member will slip into the recess each time 50 the needle is projected to normal yarn-receiving position then when this abnormal projecting movement of the hook member takes place the hook member will move without moving the latch member. If, however, 55 as is preferable, the latch member does not quite come opposite the recess 25 in the normal knitting operation then when this abnormal projecting movement of the hook member takes place the latch member will 60 be carried back into the recess and will consequently receive a very slight projecting movement but not sufficient to move it substantially out of its normal yarn-receiving position.

65 In this abnormally projected position of

the hook member the butts of the hook members slide up onto the surface 34 of the cam 13 and are thus held out of the path of the retracting cam 13 so that while the hook members hold the yarn the needles take no 70 further part in the knitting operation.

When the needles are to be restored into action either by the action of the switch cam or by the action of the dropper mechanism the butt of the hook member is depressed. As the hook member is thus retracted it moves without imparting any movement to the latch member until both members of the needle then stand in normal yarn-receiving position, any slight variation 80 in the position of the latch member being immaterial, and the needle is thus restored to action. During further retracting movement the shoulder 20 of the hook member coming in contact with the shoulder 23 of 85 the latch member depresses the latch member and immediately cams it out of the recess 25.

The entire preferred operation is graphically illustrated in the diagrammatic view 90 Fig. 4. In position 46 in Fig. 4 one of the short butt needles is shown in retracted position under the control of the cam 13. As the knitting operation continues the projecting cam 12 first projects the hook member 14 95 until the shoulder 21 comes into contact with the shoulder 24 thus moving the hook member away from the latch point and then continues the projecting movement of the hook member and with it the latch member until 100 the butt 19 rides out onto the top of the cam ring 7 and the needle is then in position 47 or the normal yarn-receiving position. If now a set of needles such as those having the longer butts 28 is to be thrown out of 105 action, the butts 28 then ride along the cam ring 7 into contact with the upper surface of the switch cam 29, which is depressed to receive them, and slide up along the cam surface. At the beginning of this movement 110 the latch member comes opposite the recess 25 and is cammed back thereinto by the action of the shoulders 21 and 24, thus releasing the latch member while the hook member continues its projected movement 115 until the butts 28 are either in line with or slightly below the top surface 34 of the cam 13 and if below are brought to the top by the inclined edges of the cam and thus the cam moves by without retracting the hook members and the needle remains out of action occupying the position shown in position 48 of Fig. 4. As the knitting operation continues and reciprocating work takes place, for example, and selected shorter butt 120 needles are to be thrown out of action the picker 37 acting in the usual manner seizes the butt 19 then resting upon the top of the cam ring 7 and by an action similar to that 125 described brings the needle to position 49 130

or a position similar to position 48. As the knitting operation continues and a selected short butt needle is to be restored into action the dropper 38 swings over the butt 19 and 5 retracts the hook member bringing it to normal yarn-receiving position and as the latch member does not move the two members of the needle then stand in position 50 which it will be noted is substantially the same, so 10 far as the yarn-receiving factor is concerned, as position 47. The only difference is that the latch member in position 50 is swung away from the hook member at the lower end of its shank and may be very slightly 15 projected beyond the position shown in 47 but not to an extent substantially affecting its yarn-receiving position. As the knitting continues and the set of needles having the longer butts are to be restored into action 20 the switch cam 29 is swung into elevated position and rides past the butts of the projected needles preferably also being moved inwardly so as to catch the butts of the shorter needles if any should remain projected. This cam then acts to retract the hook member to, and leave both members of the needle in, the same position as last described and as illustrated in position 51. As the normal knitting operation is resumed 25 and the cam 13 reaches the butts of the needles either in position 50 or 51 and retracts the hook members the latch members will be cammed out of the recesses and the needle members will assume the position 30 shown in position 46.

It will thus be seen that the cross sectional area of the needle when it is thrown out of action is not increased by projecting the latch therewith which is particularly 40 important in the finer grades of work, and further that when the needle is restored into action both members are in normal yarn-receiving position so that the knitting operation is in no way affected.

45 Having fully described my invention what I claim as new and desire to secure by Letters Patent is:

1. A knitting machine comprising a needle bed, a needle consisting of a hook member and a separate latch member recipro- 50 cable in said bed to effect the required projecting and casting off movements and movable relatively to effect the coöperation of the hook and latch, and means to give an abnormal projecting movement to the hook member to throw the needle out of action 55 without projecting the latch member substantially beyond its normal yarn-receiving position.

60 2. A knitting machine comprising a needle bed, a needle consisting of a hook member and a separate latch member recipro- 65 cable in said bed to effect the required projecting and casting off movements and movable relatively to effect the coöperation of

the hook and latch, and means to release the latch member from reciprocating movement with the hook member when the hook member is given an abnormal movement to throw the needle out of and to restore it into ac- 70

75 3. A knitting machine comprising a needle bed, a needle consisting of a hook member and a separate latch member recipro- 80 cable in said bed to effect the required projecting and casting off movements and movable relatively to effect the coöperation of the hook and latch, and means to release the latch member from and retain it against reciprocating movement with the hook member when the hook member is given an ab- 85 normal movement to throw the needle out of and to restore it into action.

4. A knitting machine needle comprising a hook member, a separate latch member, coöperating shoulders on said members for effecting the retracting movement of the latch member from the hook member and coöperating beveled shoulders on said members acting to effect the projecting movement of the latch member from the hook member so long as relative transverse movement is prevented and acting when such relative transverse movement is permitted to cam the said members apart transversely upon 90 a continued projecting movement of the hook member.

5. A knitting machine needle comprising a hook member, a separate latch member, means on said members for effecting the re- 100 tracting movement of the latch member from the hook member, and means on said members acting to effect the projecting movement of the latch member from the hook member so long as relative transverse movement is prevented and acting when such relative transverse movement is permitted to effect the transverse separation of 105 said members upon the continued projecting movement of the hook member.

6. A knitting machine needle comprising a longitudinally slotted hook member pro- 110 vided with separated opposing shoulders on its shank on the face opposite the hook, the lower shoulder being outwardly beveled, and a separate latch member having a head 115 projecting through said slot, a shank extending opposite the shouldered face of the hook member, and a shouldered projection extending between the said shoulders on the hook member, the lower shoulder on said projection being beveled to correspond with the coöperating shoulder on the hook member.

7. A knitting machine needle comprising a hook member having a projecting butt and a latch member, the said members provided with means acting to effect the coöperating movements of the latch member during the 125 retracting movements and the normal pro- 130

jecting movements of the hook member and to release the latch member from movement by the hook member upon an abnormal projecting movement of said hook member.

- 5 8. A knitting machine comprising a needle consisting of a hook member and a separate latch member, a needle bed provided with superimposed grooves for said members, the upper section of the latch 10 member groove being deeper than the lower section, coöoperating shoulders on said members for effecting the retracting movement of the latch member from the hook member, coöoperating beveled shoulders for effecting 15 the projecting movement of the latch member from the hook member, the said beveled shoulders also coöoperating upon an extended projecting movement of the hook member to cam the latch member into the deeper 20 section of its groove and to allow projecting movement of the hook member to continue without projecting farther the latch member.

9. A knitting machine having the construction and operation defined in claim 8 in which the lower end of the said deepened portion of the latch member groove is inclined and the lower opposing end of the latch member is correspondingly inclined, 25 whereby when the latch member is retracted by the hook member the said latch member is cammed out of said deepened portion.

10. A knitting machine needle bed for separate latch needles having a groove for 30 the hook member of the needle, a superimposed narrower groove for the latch member of the needle, and a superimposed recess at the end of the latch member groove to receive the latch member and hold it in 35 substantially yarn-receiving position when the needle is thrown out of action.

11. A knitting machine needle bed having

the construction defined in claim 10 in which the lower or inward end of the said recess therein is inwardly inclined. 45

12. A knitting machine comprising a cylinder, a set of needles reciprocable therein, each consisting of a hook member having a projecting butt and a latch member, the said members provided with means 50 acting to effect the coöperating movements of the latch member during the retracting movements and the normal projecting movements of the hook member and acting to release the latch members from movement by 55 the hook member upon an abnormal projecting movement of said hook member, a needle projecting cam engaging the butts of said needles and acting upon relative transverse movement of said cylinder and cam to effect 60 the normal projecting movements of said hook members, and means to give an abnormal projecting movement to the hook members of selected needles thereby to throw said needles out of action. 65

13. A latch member for a separate latch knitting machine needle having a head and a shank with the end of the shank formed to present oppositely inclined or beveled end surfaces. 70

14. A latch member for a separate latch knitting machine needle having the construction defined in claim 13 and also presenting a projecting shoulder between the head and the end of the shank. 75

15. A hook member for a separate latch knitting machine needle having a shank formed to present oppositely disposed spaced shoulders with the shoulder nearer the end of the shank outwardly inclined or 80 beveled.

In testimony whereof, I have signed my name to this specification.

PATRICK P. LA MONTAGNE.
